Re. 15,586

E. V. COOKE

VEHICLE SPRING

Original Filed Sept. 26, 1919

INVENTOR.

BY *Frank V. Cooke*
Raymond A. Parker
ATTORNEY.

ATTORNEY.

UNITED STATES PATENT OFFICE.

FRANK V. COOKE, OF DETROIT, MICHIGAN, ASSIGNEE TO KARL B. GODDARD, OF DETROIT, MICHIGAN.

VEHICLE SPRING.

Original No. 1,344,792, dated June 29, 1920, Serial No. 326,445, filed September 26, 1919. Application for reissue filed November 30, 1921. Serial No. 518,989.

To all whom it may concern:

Be it known that I, FRANK V. COOKE, who am a citizen of the United States, residing at Detroit, county of Wayne, State 5 of Michigan, have invented a certain new and useful Improvement in Vehicle Springs, and declare the following to be a full, clear, and exact description of the same, such as will enable others skilled in the art to 10 which it pertains to make and use the same, reference being had to the accompanying drawings, which form a part of this specification.

My invention relates to vehicle springs 15 and has for its object to provide an improved spring in which the resilient force is applied advantageously and a compact and convenient construction provided.

I secure this object in the apparatus shown 20 in the accompanying drawings, in which—

Figure 1 is a front elevation of a portion of a vehicle having a spring apparatus embodying my invention secured thereto.

Fig. 2 is a section on the line A—A of 25 Fig. 1.

a is a transverse bar of the vehicle body or chassis. a² represents a U-shaped extension from the cross bar a, the open portion being downward. This is at the center of 30 the body. a³ are bolts spaced from each other and extending parallel to each other between the two branches of the U-shaped extension a². a⁴ is a plate intermediate of the branches of the U-shaped part and parallel thereto.

d is the vehicle axle. This is hollowed out at the center as shown at d² to make room for the U-shaped extension a².

b is a leaf spring approximately straight 40 from end to end extending between one of the branches of the U-shaped piece a², and the center plate a⁴ and having one end pivoted to the lower ends of a depending swinging link b². The other end is pivoted 45 at e to a pin extending laterally from the axle near one end thereof. c is a second spring entirely similar to the spring b pivoted at e² and extending laterally to the other end of the axle d and extending 50 through the U-shaped piece a² between the plate a⁴ and the other branch of the U-shaped part and similarly pivoted to the lower end of a depending swinging link c².

The springs b and c are loosely embraced

by the pins a³ which in connection with the 55 U-shaped piece form a clamp for securing said springs and constraining their relative longitudinal movement within said forked member, each spring being free to move longitudinally within said forked member relative thereof.

While it is preferable to secure both of the upper ends of the springs b and c to swinging links, as shown, the apparatus will operate to perform its function if only one 65 end of a spring is so pivoted or if one or both of the upper ends of the springs are allowed to slide through a socket, as is done with reference to cantaliver constructions of the rear springs. 70

The above-described construction secures three points of resilient constraint to the movement of the body and great freedom of spring action.

The spring is shown connected to a front 75 axle, in which case the lower ends would be secured near the center of gravity of the steering knuckle.

The upper bolt a³ forms a pivotal support at the center and the springs are secured so as to provide an angular freedom of movement, or pivotal action, at each end. I use the word "pivotal" as co-extensive with its functional implication. 80

Claims:

1. The combination of a vehicle body, an axle, a spring pivoted to one side of the body and to the end of the axle farthest from said side, a second spring pivoted to the other side of the body and to the other end of said axle, a forked member depending from said body adapted to embrace said springs in such a manner as to permit movement of the springs longitudinally, but to restrain movement laterally and vertically 90 within said forked member, said forked member adapted to form an upper fulcrum support for said springs. 95

2. The combination of a vehicle body, an axle, a spring pivoted to one side of the body and to the end of the axle farthest from said side, a second spring pivoted to the other side of the body and to the other end of said axle, a forked member depending from the body adapted to embrace the intermediate portions of said springs so as to form a fulcrum therefor, and so embracing said springs as to permit relative move- 100
105

ment of the body and springs longitudinally of the springs but to prevent lateral movement of the springs.

3. The combination of a vehicle body, an axle, a spring pivoted to one side of the body and to the end of the axle farthest from said side, a second spring pivoted at the other side of the body and to the other end of the axle, a forked member depending from the body in such a manner as to embrace said springs and prevent lateral distortion thereof, pins carried transversely of said forked member above and below said springs embracing said springs in such a manner as to restrain the vertical movement of said springs within said forked member but to permit the longitudinal movement therein.

4. The combination of a vehicle body, an axle, a spring pivoted to one side of the body and to the end of the axle farthest from said side, a second spring pivoted at the other side of the body and to the other end of the axle, a forked member comprising a series of parallel forks depending from said body adapted to individually embrace said springs in such a manner as to prevent lateral distortion thereof but to permit free longitudinal movement of said springs within said forked member, a pin extending transversely through the forks of said depending member above said springs adapted to serve as a fulcrum therefor, a second pin extending transversely through the forks of said depending member below said springs in such manner as to restrain vertical movement of said springs within said forked member but permitting the longitudinal movement of said springs therein.

5. The combination of a vehicle body, an axle, a spring pivoted to one side of the body and to the end of the axle farthest from said side, a second spring pivoted to the other side of the body and to the other

end of said axle, a rigid body-supporting member carried by the body and bearing upon each of said springs intermediate its ends in such a manner as to permit individual longitudinal movement of each spring thereover.

6. The combination of a vehicle body, and axle, a spring shackled to one side of the body and pivoted to the end of the axle farthest from said side, a second spring shackled to the other side of the body and pivoted to the other end of said axle, rigid body supporting means bearing on each of said springs intermediate its ends so the body load will be carried thereby and in such a manner as to permit longitudinal movement of each spring relative said means.

7. In a resilient suspension for a vehicle comprising an axle and a load supporting member above the axle, in combination, springs connected to the ends of the axle and to the respectively opposite sides of the load supporting member and crossing between the axle and the load supporting member; rigid body supporting means bearing on said springs at their crossing point and so constructed and arranged as to permit longitudinal movement of the springs thereover.

8. The combination of a vehicle body, an axle, a spring pivoted to one side of the body and to the end of the axle farthest from said side, a second spring pivoted to the other side of the body and to the other end of said axle, a stationary fulcrum member carried by the body to bear on said springs at their crossing point so each spring may travel individually longitudinally thereover.

In testimony whereof, I sign this specification.

FRANK V. COOKE. [L. S.]
